UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

CLAMP.

1,361,956.

Specification of Letters Patent. Patented Dec. 14, 1920.

Application filed February 20, 1918. Serial No. 218,245.

To all whom it may concern:

Be it known that I, WILLIAM BARTHOLOMEW, a citizen of the United States, and resident of Chicago, in the county of Cook and State of Illinois, have invented certain new and useful Improvements in Clamps, of which the following is a specification.

This invention relates to clamps, and particularly to clamps for bands which are drawn tightly around cylindrical washing receptacles or tubs and the like.

The object of this invention is to provide a simple and improv[er] clamp for bands adapted to meet the requirements of the use to which it is subjected.

Generally speaking, this and other objects are accomplished by providing a clamp for connecting the ends of a band, including duplicate members secured to the ends of the band, each member having an end receiving loop, and means connecting said members for changing their relative position for tightening or loosening the band.

The invention is illustrated on the accompanying sheet of drawings, in which—

Figure 1 is a fragmentary sectional view of a cylindrical tub showing my clamp applied to a band encircling the tub;

Fig. 2 is a front elevation of one of the members forming my clamp;

Fig. 3 is a side elevation of the same; and,

Fig. 4 is an enlarged sectional view showing the co-operative association between the end of the band and the clamping members.

Bands have been adjustably secured around cylindrical receptacles of a washing machine, and also around other devices and receptacles. The means for tightening and loosening these bands have taken various shapes. In my particular clamp for the purpose indicated, I have provided a novel arrangement which is adapted for successful commercial usage.

Reference being had to the drawings, it will be noted that I have shown my invention in connection with a cylindrical receptacle, including a plurality of members 10 which are connected by suitable joints 11, a

band 12 encircling the receptacle for the purpose of holding the members 10 in such relation with respect to each other as to prevent leakage of water or the like from

the cylindrical member or tub. The clamp for drawing the ends of the band together 55 include preferably two duplicate interchangeable members 13, each of which has a loop portion 14 in which is received the bent-back end portion 15 of the band 12. Each of the clamping members 13 also has a 60 groove 16 in the under side thereof, and it will be noted that said groove is tapered so that the band 12 may rest completely therein, while at the same time the band engages the periphery of the cylindrical member. The band 12 near its ends is provided with portions 17 which extend outwardly from the cylindrical member and have apertures 18 through which passes a threaded member 19, which also extends through apertures 20 within the members 13 and which are in alinement with the openings 18 in the band 12. This threaded member 19 extends in a straight line and connects the ends of the band with the co-operation of the 75 clamping members 13. Nuts 21 are threaded onto the outer ends of the threaded member 19 and engage the rear walls of the clamping members 13. These nuts may be drawn up to any desirable degree to tighten the 80 band 12 the desired amount. Likewise, the band may be loosened by turning the nuts 21 in an opposite direction.

In connecting the parts, it is merely necessary to slip each of the clamp members 13 85 onto the ends of the band 12 in such a manner that the back-turned portions 15 thereof pass into the loops 14 and the main part of the band rests in the grooves 16 in the bottom of the clamping members. These 90 grooves 16 are made at such an angle with respect to the apertures 20 as to overcome any tilting action of the members 13 about the inner front corner or edge 22 thereof. In this way the clamping action is made secure and can be depended upon. The openings of the loops 14 of the clamping members preferably are in communication with the apertures 20 to make each of said members 13 as light as possible.

It is my intention to cover all modifications of the invention falling within the spirit and scope of the following claims.

I claim:

1. A clamp for operatively connecting the 105 ends of a band which has its ends turned

back forming loops, including duplicate members secured to the ends of the band, each member having a groove adapted to overlie the band, and a loop spaced from 5 said groove adapted to receive the turned back end of the band, said member having an aperture therethrough between said groove and said loop in register with an aperture through the band loop, and means 10 extending through said aperture connecting said members for changing the relative position for varying the tension of the band.

2. A clamp for operatively connecting the ends of a band which has its ends turned 15 back forming loops, including duplicate members secured to the ends of the band, each member having an end receiving loop and an aperture, said aperture being positioned between the loop and the band, and 20 means extending through the apertures connecting said members for changing their relative positions for varying the tension of the band.

3. A clamp for operatively connecting the 25 ends of a band which has its ends turned back forming loops, including duplicate members secured to the ends of the band, each member having an end receiving loop, a band-receiving groove and an aperture, 30 said aperture being positioned between the loop and the band, and means extending through said apertures connecting said

members for changing their relative position for varying the tension of the band.

4. A clamp for operatively connecting the 35 ends of a band which has its ends turned back forming loops, including a member having an end receiving loop, an aperture and a band seating groove, said aperture being positioned between the loop and the 40 band, the groove and aperture being at an angle with respect to each other to prevent a turning movement of said member when the clamp is tightened.

5. As a new article of manufacture, a 45 clamp member having a band-receiving loop, an aperture for an adjusting bolt, and a groove for seating a band, said loop being on the opposite side of the clamp from the band-seating groove.

6. As a new article of manufacture, a clamp member having a band-receiving loop, an aperture for an adjusting bolt, and a groove for seating the band extending at an angle with respect to said aperture, said loop 55 being on the opposite side of the clamp from the band-seating groove.

Signed at Chicago, Illinois, this 14th day of February, A. D. 1918.

WILLIAM BARTHOLOMEW.
